CLAIM

I claim the ornamental design for a bed lamp, as shown and described.

DESCRIPTION

FIG. 1 is a front-perspective view of a bed lamp, according to one embodiment, with reference to an enlarged view of FIG. 9.

FIG. 2 is a bottom-perspective view of the bed lamp of FIG. 1.

FIG. 3 is a front view of the bed lamp of FIG. 1.

FIG. 4 is a rear view of the bed lamp of FIG. 1.

FIG. 5 is a left-side view of the bed lamp of FIG. 1.

FIG. 6 is a right-side view of the bed lamp of FIG. 1.

FIG. 7 is a top view of the bed lamp of FIG. 1.

FIG. 8 is a bottom view of the bed lamp of FIG. 1; and, FIG. 9 is an enlarged view of the bed lamp of FIG. 1 taken along line 9.

The broken line disclosure represents portions of the lamp which form no part of the claimed design.
